ELECTRIC SWITCH

James A. Umbarger, Cheboygan, Mich.

Application August 24, 1956, Serial No. 42,746

Term of patent 14 years

(Cl. D26—13)

FIG.1

FIG.2

FIG.4

FIG.3

Figure 1 is a perspective view of an electric switch showing my novel design;

Figure 2 is a top plan view of the electric switch;

Figure 3 is an end elevational view; and

Figure 4 is a side elevational view.

The broken line showing of a connecting cord and spring clips is for illustrative purposes only.

I claim:

The ornamental design for an electric switch, as shown and described.
